CARRYING CASE FOR TYPEWRITERS

Jan Streng, Mason, N. H., assignor to Remington Rand Inc., Buffalo, N. Y., a corporation of Delaware

Application August 5, 1941, Serial No. 405,508

2 Claims. (Cl. 45—68.2)

This invention relates to carrying cases for portable typewriters, and more particularly to an improved stationery holding device for such carrying cases.

An object of the present invention is to provide a carrying case for portable typewriters having a stationery holding device therein which is very simple in construction and yet highly effective in use, and which does not require the dimensions of the carrying case to be enlarged nor add materially to the manufacturing cost thereof.

A further and more specific object of the present invention is to provide a carrying case for a portable typewriter having base and cover sections with a stationery supporting member adapted to normally occupy an unused portion within the carrying case when closed upon the typewriter, and arranged to move from this position to a position affording access to the stationery carried by this supporting member when the cover section is opened or removed from the base section.

Other objects, purposes and characteristic features of the present invention will appear as the description thereof progresses, during which references will be made to the accompanying drawings, wherein:

Fig. 1 is a perspective view of a cover section of a carrying case detached from the base section and provided with a stationery holding device arranged in accordance with the present invention.

Fig. 2 is a side sectional view taken through the cover section, base section and the stationery holding device of the present carrying case.

Fig. 3 is a fragmentary sectional view of a detent arrangement which may be used with the present stationery holding device, the section being taken on line 3—3 of Fig. 2.

Fig. 4 is another fragmentary sectional view taken on line 4—4 of Fig. 2 and showing a method of pivotally mounting the present stationery holding device within the cover section of the carrying case.

The carrying case illustrated in the present drawings is of a two-section construction, one section being a base 5 having a shallow depression 6 for receiving the lower portion of a portable typewriting machine. The outline of a portable typewriting machine T is illustrated in Fig. 2 by dot and dash lines, and the usual mechanism may be provided for detachably securing this machine in its illustrated position on the base section 5.

The other section of the carrying case is in the form of a cover having a top wall 7, front wall 8, rear wall 9 and side walls 10. All of these walls are permanently united to form a box-like cover

with a lower edge fitting upon the upper edge of the base section 5 to entirely enclose the typewriting machine T.

The cover section is pivotally and detachably secured at its rear portion to the rear portion of the base section 5 by hinge straps 12 secured in spaced relation at the lower edge of the rear cover wall 9, and these straps have pointed pivot pins 13 rigidly secured thereto which are adapted to enter companion cylindrical openings in hinge straps 14 secured in spaced relationship at the rear portion of the base section 5 as shown in Fig. 2. These hinge members 12, 13 and 14 serve to retain the rear portion of the cover section in position relative to the rear portion of the base section 5 as shown in Fig. 2, and permit the cover section to be moved upwardly and rearwardly relative to the base section and in such position the cover section may be moved laterally to separate pins 13 from the hinge straps 14 and permit the cover section to be entirely removed as shown in Fig. 1.

When the cover section is closed upon the base section, the front portions of these two sections may be locked together by any suitable means such as the usual two-part locking latch mechanism illustrated in Fig. 2 which comprises a lockable latch mechanism 16 mounted at the front of the base section 5 to cooperate with companion latching mechanism 17 mounted at the lower edge of the front wall 8 of the cover section. With the cover section thus latched in place upon the base section, the case may be carried in an upright position with the rear portion of the typewriting machine T downward, and a suitable handle 18 may be secured at the central portion of the front wall 8 of the cover section.

The stationery holding device of the present invention is arranged to occupy a space within the cover section which is not occupied by the typewriting machine T when the cover section is closed upon the base section, and this stationery holding device is mounted within the cover section for movement from this position to a position wherein the stationery held thereby is readily accessible when the cover section is opened and removed. The illustrated form of this stationery holding device comprises a supporting member S which may be formed of a sheet of rigid material such as fiber or metal and extends between the sides 10 of the cover section and is normally disposed above the keyboard of the typewriter T and between the front end of the line space lever and the front wall 8 of the cover section.

The supporting member S is provided with straight end portions 20 and 21 separated by a curved portion 22. When the supporting member S is in normal position as shown in full lines in Fig. 2, the portion 20 extends substantially parallel with the top wall 7 of the cover section, and the portion 21 is substantially parallel with the front wall 8 of the cover section. The side edges of supporting member S including straight portions 20 and 21 and curved portion 22 are provided with flange portions 24 which in the illustrated form are of a hollow construction with a substantially rectangular cross section as shown in Fig. 3, but it may be found preferable to make these flange portions of a suitable solid material such as plywood.

A pocket is formed at the rearward end of stationary supporting member S by an upright cross member 26 joined to the rear edge of the straight section 20 and a top strip 27 which is joined to the upper edge of strip 26 and extends above and parallel with the rear straight portion 20 of the supporting member. A similar pocket is formed at the front end of stationary supporting member S by a strip 30 joined to the lower edge of the straight portion 21 and a strip 31 which is joined to the front edge of strip 30 and extends upwardly therefrom in spaced parallel relation to the straight section 21. The strips 27 and 31 may be joined or integral with the top edge portions of the flange portions 24 as shown in Fig. 1.

This supporting member S with the pockets at each end thereof provides a means for holding sheets of paper P with the ends thereof resting in the lower pocket and the other ends in the rearward pocket so that the intermediate portions of the sheets extend over and are supported by the curved portion 22 of the supporting member. In addition, a supply of envelopes E may be provided in the front pocket between the sheets of paper P and the front strip 31.

When the cover section is closed upon the base section as shown in Fig. 2, the stationery supporting means just described is disposed above the keyboard of the typewriting machine T in the space which is not otherwise occupied by any part of the machine. In this position, the stationery P and E is not readily accessible and means are provided in accordance with the present invention for mounting this stationery holding structure within the cover section for movement from this position to a position shown in Fig. 1 or in dotted lines in Fig. 2 when the cover section is opened or removed from the base section to afford convenient access to the stationery.

The stationery holding structure is pivotally mounted at the rear end portion thereof to the upper central portion of the cover section by side extensions 35 having openings receiving pivot pins 36 suitably secured to the side walls 10 of the cover section. The rear end of the stationery holding structure is thus supported by the extensions 35 and pivot pins 36, and means are provided for normally holding the front end of this structure against displacement from normal position shown in Fig. 2 when the cover section is closed. This means is shown in Fig. 3 in the form of a detent arrangement acting on the sides of flange portions 24 and each of these detent devices comprises a cup-shaped member 38 pressed into an opening in the companion side wall 10 and carrying a spring 39 arranged to press a detent ball 40 outwardly toward a retaining rim around the edge of cup 38. Each of

detent balls 40 may be arranged to enter a depression in the outer surface of the associated side flange member 24 as shown in Fig. 3 to resiliently retain the front end of the stationery holding structure against displacement from its position shown in Fig. 2 when the cover section is closed.

When it is desired to use the typewriting machine T, the cover section may be moved upwardly and rearwardly about the pivot pin 13 and completely removed therefrom if desired as shown in Fig. 1. In this position, the stationery holding structure may be forcibly moved from its normal position against the action of the detent means and swung about the pivot pins 36 to its position shown in Fig. 1 wherein the lower strip 30 rests against the inner edge of the rear wall 9 of the cover section. This position of the stationery holding structure affords access to the supporting member and pockets for convenient insertion or removal of the paper P and envelopes E. When it is desired to replace the cover section, the stationery holding structure is moved about the pivots 36 to its position shown in Fig. 2 wherein it is retained by the detent devices, thus permitting the cover to be replaced upon the base section 5 without interference with any part of the typewriting machine.

A carrying case for portable typewriters has thus been provided having a very simple and yet highly effective stationery holding arrangement mounted therein. It will be clear that this stationery holding arrangement normally occupies a position within the carrying case which is not required for any other purpose and is movable therefrom when the cover section is opened to a position affording convenient access thereto. The arrangement for holding the stationery in the form of papers and envelopes or the like is of a very simple construction which may be easily manufactured at a very low cost and which does not add to the dimensions of the carrying case and adds a minimum of weight to the combined assembly.

The stationery holding structure as described provides a pocket of sufficient length from cross member 26 to strip 30 for receiving the conventional commercial letter size sheets, usually 8½ x 11 inches, in the manner shown in Fig. 2. Letter size sheets are not adapted to housing in the usual size of portable typewriter case because they are substantially the size of the length and width of the cover and therefore too large. As a result there is insufficient space in a holder for letter size stationery in the usual portable typewriter case without folding or creasing the sheets and without increasing the size of the cover dimensions of the case both vertically and horizontally. The present structure therefore merely bends the letter size sheets about curved portion 22 and provides adequate storage space for such sheets in the unused front top portion of the cover without increasing its size and without creasing or folding the sheets.

It is to be understood that various changes may be made in the specific construction illustrated and described, and certain parts thereof may be employed without others, without departing from the spirit and scope of the present invention as defined by the accompanying claims.

The invention claimed is:

1. In a carrying case for a portable typewriter, a base section for supporting the typewriter, a cover section detachably connected to said base

section to enclose the typewriter, a stationery supporting member having a curved central portion with one end portion disposed substantially parallel with the front side of said cover section and the other end portion disposed substantially parallel with the top side of said cover section, a pocket at each of said end portions of the stationery supporting member, and means pivotally mounting said stationery supporting member at the upper central portion of said cover section to permit movement of the stationery supporting member downwardly against the lower front edge of the cover section when raised from the base section.

2. In a carrying case for a portable typewriter wherein the case has a base section for supporting a typewriter and a cover section detachably connected to said base section and having top, side, front and rear walls enclosing a typewriter mounted on said base section and having the lower edges of the side, front and rear walls formed for seating engagement on said base section in closed position, said cover having the rear portions of the top, side and rear walls in adjacent relation to the typewriter housed therein and having the forward portions of the side, top and front walls spaced from the typewriter and forming a compartment over the typewriter keyboard extending rearwardly to the central portion of the casing, and a stationery supporting member

in combination with said casing mounted in said compartment and having a supporting member formed with substantially straight end portions extending away from opposite ends of a curved central portion in substantially perpendicular relation to each other, pocket-forming means on the outer faces of said straight end portions opening toward the central portion, means pivotally connecting one end of said supporting member to the cover at the upper central portion of said cover with the opposite end portion lying adjacent and parallel to said front wall, and latch means at the lower edge of the walls of said cover section engaging the free lower end of said supporting member for retaining said supporting member in said compartment with the central open pocket portions facing the front upper corner of said casing whereby said cover cooperates with said supporting member for retaining letter size commercial correspondence sheets with opposite ends engaged in the pockets at opposite ends of said supporting member and said supporting member being adapted to have the free end adjacent said front wall moved outwardly from said compartment about said pivot means upon disengagement from said latch means for providing access to said pockets and paper after said cover section has been moved to open position.

JAN STRENG.
